UNITED STATES PATENT OFFICE.

FRANK N. ROEHRICH, OF JERSEY CITY, NEW JERSEY, ASSIGNOR TO GEORGE P. CARROLL, OF BRIDGEPORT, CONNECTICUT.

REFRIGERATOR-THERMOSTAT.

1,172,740.

Specification of Letters Patent. Patented Feb. 22, 1916.

Application filed October 11, 1912. Serial No. 725,180.

To all whom it may concern:

Be it known that I, FRANK N. ROEHRICH, a citizen of the United States, residing at Jersey City, in the county of Hudson and 5 State of New Jersey, have invented a new and useful Refrigerator-Thermostat, of which the following is a specification.

My invention relates to improvements in thermostats used either in automatic refrigerating systems or in automatic heating systems, but especially in the former. Such 10 thermostats are divisible into three general classes.

First, thermostats with their motor member made of two flat strips, such as brass 15 and steel or rubber and steel, with their flat surfaces secured together and fashioned in the form of a tongue or a helix, with one end pivoted and the other end free, so that with 20 a rise of temperature the greater expansion of one material such as the brass, will force the free end of the member in one direction, into contact with a stationary high temperature contact, and so that with a fall of tem- 25 perature the greater contraction of this same material will force the free end of the member in the opposite direction, into contact with a stationary low temperature contact. Such thermostats, however, have very 30 little motor power and are adapted only for making and breaking electric contacts.

Second, thermostats consisting of a chamber casing inclosing a high tension gas or vapor, such as ammonia, and having as their 35 motor member a movable wall forming one side of the chamber. Such a wall may be in the form of a diaphragm, clamped at its edges, or it may be a Bourdon pressure tube. In one case, an increase of temperature and 40 pressure moves the center of the diaphragm outward, in opposition to a strong spring, and a decrease of temperature and pressure permits the spring to move the center of the diaphragm inward. In the other case, the 45 free end of the tube similarly overcomes or yields to a spring. While the pressure of the gas or vapor in such a thermostat, at any given temperature, is high, yet the change of pressure, occurring with a few degrees 50 rise or fall of temperature, is relatively slight and the consequent net action upon or yielding to the spring is trifling. Such thermostats, also, are of slight power. The

advantages of both these two classes of thermostats is that the to-and-fro movements of 55 their motor members are very considerable, being as much, if desired, as an eighth of an inch, or more, within a few degrees change of temperature.

Third, thermostats that depend on the 60 longitudinal expansion and contraction of some solid, such as copper or hard rubber, as the motor member, to operate the short end or ends of one or of a series of pivoted levers. Here the advantage is that the 65 power exerted by the motor member is very great. But the disadvantages are that, for a slight change of temperature, the to-and-fro movements of the motor member are very slight; and, unless the parts are made 70 very heavy, there is a yielding of the material which greatly reduces the movements that are theoretically obtainable.

The main purpose of my invention is to 75 construct a thermostat that will have a strength comparable with that of the third class, that will have a range of movements comparable with that of the first and second classes, that will avoid the disadvantages 80 of all three classes, and that will be especially adapted for use in connection with refrigerating machines.

My invention further relates to improvements in apparatus wherein variations of 85 fluid pressure result in movements of a diaphragm, forming part of the casing wall containing the fluid, so as to move mechanism adjacent to the diaphragm. In such a construction my purpose is to so connect a diaphragm with a casing wall that the dia- 90 phragm, though very thin, will not break under the stress of normal working fluid pressures.

My invention further relates to improvements in means for adjusting the range of 95 circular movement of the outer end of a lever that is acted upon, near its inner or pivoted end, by motor mechanism, especially when the lever constitutes part of a thermostat. In such a construction my purpose 100 is to make such adjustments easy, accurate and strong.

There are also certain detail improvements of construction as will appear.

The means employed for accomplishing 105 these purposes are disclosed in the accom-

panying drawings and in the description relating thereto.

In the drawings, Figure 1 is a partial front elevation and a partial vertical section of one form of my invention. Fig. 2 is a partial plan view and a partial horizontal section through the line 2—2 of the preceding figure. Fig. 3 is an enlarged detail view of a part of the vertical section shown in Fig. 1, and showing the means of connection between a diaphragm and its adjacent wall. Fig. 4 is a front elevation of the structure of Fig. 1, but with certain parts on the upper right side omitted. Fig. 5 is a left end elevation of a part of the preceding figure. Fig. 6 is a partial right end elevation and a partial vertical section of the structure shown in the preceding figure. Fig. 7 is a partial vertical section and a partial front elevation of a modified form of my invention, through the line 7—7 of the next figure, as attached to the right side wall of a compartment, such as a refrigerator. Fig. 8 is a partial right end elevation and a partial vertical section through the line 8—8 of the preceding figure. Fig. 9 is an enlarged detail view of a part of Fig. 7.

First considering Figs. 1 to 6 inclusive: A pipe 1, shown in broken vertical section, is externally threaded, top and bottom, and should be of such length as required for the purposes of its use, as will be hereinafter explained. A cup nut 2 has its side walls internally threaded and through the opening in its end wall is adapted to be slid over the lower end of the pipe 1. A lower casing 3 has an internally threaded section for screwing over the lower end of the pipe 1; it has, at the top above its internally threaded section, a recess containing a packing 4 and above the packing a packing ring 5; and it is externally threaded at its extreme top. After the nut 2 has been slid over the lower end of the pipe 1, the casing 3, containing the packing 4 and the ring 5, is screwed around the lower end of the pipe; and then the nut is screwed around the top of the casing so that the ring compresses the packing and makes a tight joint between the pipe and the casing. The casing 3 also has, below its internally threaded section, a flanged section, of an internal diameter very considerably greater than that of the pipe 1, having a recess adapted to contain a gasket 6 and being internally threaded below the gasket.

A flexible relief diaphragm 7, preferably of thin metal, rests against the under side of the gasket 6 and tends a little to bend upward and inward. Adjacent to the under side of the diaphragm 7 is a disk member 8, having its disk part practically coextensive with the movable part of the diaphragm and having a stem extending downward and

threaded at its lower end. A compressing member 9 has an externally threaded upper section, corresponding to the lower internally threaded part of the casing 3; it has a plain upper inner section, fitting around and under the disk part of the member 8 but permitting the latter to be slightly reciprocated; and it has an internally threaded lower section. After the gasket 6 has been placed in its recess, after the diaphragm 7 has been placed against the gasket and after the member 8 has been placed with its disk part against the diaphragm, the member 9 is screwed into the casing 3 so as to compress the gasket and to make a tight joint between the casing and the diaphragm.

A sleeve 10 is externally threaded top and bottom and has a central nut section whereby it is screwed into the lower section of the member 9. A heavy helical compression spring 11 is adapted to surround the stem of the member 8 and to abut against its disk part. A cap 12 has a vertical central opening large enough for the passage through it of the lower end of the stem of the member 8, and it is internally threaded for screwing around the lower end of the sleeve 10. After the cap 12 has been screwed on to the sleeve 10 so that the threaded extremity of the member 8 projects through, a stop nut 13 is screwed around this extremity until the spring 11 has been given a desired tension and then the nut 13 is held in place by a lock nut 14. Finally the cap 12 is screwed up just enough to cause the member 8 to bear against the diaphragm 7 without forcing it inward. The nut 12 may be screwed up, as described, until the spring 11 has been compressed to such an extent that it will not yield to pressure, on the upper side of the diaphragm 7, until such pressure exceeds say 200 pounds per square inch; but the diaphragm and spring should be so proportioned that, after some such pressure has been exceeded, they will yield sufficiently to permit of such an expansion of the liquid above the diaphragm as will occur, in manner to be described, up to the maximum atmospheric temperature, which may be taken as 110 degrees.

An intermediate casing 15 has an internally threaded lower section, into which the upper end of the pipe 1 is screwed; it has an externally threaded upper hub 16; it has a vertical cylindrical chamber extending from top to bottom; and it has an opening extending from this chamber through an integral hub 17 to the right. As the opening through the hub 17 proceeds to the right from the chamber of the casing 15, there is first a threaded section, second a plain section of greater diameter, third a packing section of yet greater diameter and finally a threaded section of greatest diameter. A rod-like regulator 18 is externally threaded

at its inner end so that it may be screwed into the innermost section of the hub 17; it has a central longitudinal passage 19 extending from its inner end for a distance 5 nearly equal to the length of the hub from the inner end of the latter as far as the outer end of the plain section; it has a transverse passage 20, extending from the outer end of the passage 19 to the outside of the regulator, so as to connect the passage 18 with the space in the plain section; and it terminates in a wrench section at its outer end. After the space above the diaphragm 7 has been filled with liquid, as will be described, 10 and after the regulator 18 has been screwed into the hub 17, a packing ring 21 is placed in the packing section of the hub; a lock nut 22 is screwed around a gland nut 23; the nut 23 is screwed into the outermost 15 threaded section of the hub, so as to compress the ring and to make a tight joint between the hub and the regulator; and then the nut 22 is screwed up so as to hold in place the nut 23. It is apparent that, after 20 loosening the nuts 22 and 23, the regulator 18 may be screwed farther in or farther out and that thereafter the nuts may again be tightened.

The hub 16 has near its top, around its 30 contained chamber and above its threads, a section 24 of reduced diameter and, surmounting the section, an annular and slightly convex rim 25 of the shape best shown in Fig. 3. The outer slope of the 35 rim 25 is longer and extends farther down than does its inner slope. Resting on the shoulder formed by the reduction of the diameter of the hub 16, and around the section 24, is a gasket 26 that extends upward 40 as far as the bottom of the outer slope of the rim 25. A motor diaphragm 27, preferably of very thin metal, rests on the rim 25 and the gasket 26.

An upper casing 28 has a horizontal partition 29, with a cylindrical opening extending centrally and vertically through the partition; it has below the partition a vertical cylindrical reciprocating chamber of substantially the same diameter as the 45 chamber in the casing 15; it has at its extreme lower end an internally threaded section for screwing on to the hub 16; it has above this threaded section a recess section 50 so as to surround and bear upon the outer edge of the diaphragm 27 and the gasket 26; and, between the recess section and the reciprocating chamber, it has a concave formation, as best shown in exaggerated form in Fig. 3, so as to permit the diaphragm to 55 swell out a slight distance and then to bear even upon the casing. Resting flat upon the diaphragm 27, and adapted for reciprocation in the reciprocating chamber of the casing 28, is a foot 30, having on top a cylindrical cavity. When the casing 28, contain-

ing the foot 30, is screwed down upon the hub 16, it compresses an annular section of the diaphragm 27 both upon the gasket 26 and also upon the lower edge of the outer slope of the rim 25; and it compresses the 70 gasket so as to make a tight joint between the hub and the diaphragm.

The parts are so constructed and formed that when the diaphragm 27 occupies a central position, as shown, it has its periphery 75 resting flat upon the gasket 26; it has an annular section inclined upward and resting on the outer slope of the rim 25; and it has its central part extending flatly across the space within the top of the rim. But when 80 the diaphragm 27 is forced inward, an annular section of its central part tends to rest on the inner slope of the rim 25. And when the diaphragm 27 is forced outward, the central part swells outward so that, as 85 viewed in vertical section, this central part tends to make smooth curves with the annular section resting on the outer slope of the rim 25. By reason of this construction, the greatest stress on the diaphragm 27, on 90 an outward movement, is upon an annular section outside of another annular section upon which is the greatest stress upon an inward movement of the diaphragm.

The compressing of the diaphragm 27, 95 upon the lower edge of the outer slope of the rim 25, leaves an annular section, around the upper part of the slope, open to the action of the liquid in the casing 15, on outward movements of the diaphragm. The concavity of the casing 28 above the diaphragm is such that, when the foot is moved outward say a thirty-second of an inch, the diaphragm may bear evenly on the foot and casing and may be backed and supported thereby at all points just as effectually as if resting against a solid wall. Assuming that the outward movement of the foot 30 is 100 properly limited, as will be shown, this construction of the diaphragm and of its adjacent parts effectually protects the diaphragm against injury by fluid pressure on its underside, however great such pressure may be. The construction of the rim 24 above referred to, on an inward movement of the 105 diaphragm 27, shifts the stress from an outer annular section of the diaphragm to an inner annular section. So that the total effect is to make the diaphragm 27, if of 110 suitable material, to be very durable.

It also is to be noted that the diameter of the foot 30 is nearly as great as the diameter of the movable part of the diaphragm 27. By this construction, it being assumed that the diaphragm 27 is of such material and 115 thinness as to exert a minimum of resistance, the diaphragm, as an instrument for moving the foot 30, approximates a piston in efficiency. It would be otherwise with a diaphragm of relatively small diameter. This 120 125 130

construction would be of even greater importance if the diaphragm 30 were to be acted upon by a gas or vapor, instead of, as preferred in the present structure as an entirety, by a liquid.

The upper part of the casing 28 has above its partition 29 a vertical cylindrical reciprocating chamber; it has above this chamber at its top a section that is threaded both internally and externally; and, for a distance extending from its top nearly to its part screwing around the hub 16, its exterior diameter is lessened sufficiently so as to leave a hexagonal shoulder at its lower end. A stop ring 31 and a lock ring 32 are adapted to reciprocate slightly in the reciprocating chamber of the casing 28 above its partition 29. A reciprocating rod 33 has, at its lower end, a section of reduced diameter, adapted for reciprocation through the opening in the partition 29 and to fit into the cavity of the foot 30; it has, above its section of reduced diameter, an intermediate threaded section for screwing into the rings 31 and 32; and it has, above its threaded section and for most of its length, a plain section. After the rod 33 has been screwed into the rings 31 and 32, and after the ring 32 has been screwed up so as to hold the ring 31 in proper longitudinal position, the rod is inserted into the casing 27 so that its lower end passes through the partition 29 and occupies the cavity in the foot 30 and so that the ring 31 rests on the partition. An externally threaded stop sleeve 34 is adapted for screwing into the top of the casing 27 so as to loosely surround the rod 33; and it has a nut section at its top. A lock nut 35 is adapted for screwing around the sleeve 34 nearly up to the nut section. After the nut 35 has been screwed up on the sleeve 34, the sleeve is screwed into the casing 27 until its lower end is a short distance above the ring 32 and then the nut is screwed down so as to hold the sleeve in its longitudinal position. Surmounting the top of the rod 33 is a knife edge bearing 36, having a cavity on its under side fitting over the rod.

The parts are so constructed and adjusted that, when the rod 33 is in its lowest position, it bears upon the foot 30 so as to very slightly depress the diaphragm 27; but it is prevented from further thrusting upon the diaphragm by the contact of the ring 31 with the partition 29; and the foot and rod are free to move upward a thirty-second of an inch, but no farther, by the contact of the ring 32 with the sleeve 34. Obviously the parts could be so adjusted as to provide for some other range of movement of the reciprocating parts. But a range of a thirty-second of an inch is selected because that is sufficient and yet is not so great as to strain the diaphragm 27. It is intended, moreover, that whatever range of movement is once

selected, such range, once selected, shall remain a constant throughout all adjustments of the thermostat.

A bracket 37 has a vertical part and it has a top cross arm and a bottom cross arm, 70 to the right of the vertical part, with holes through each arm at each end, for bolting or screwing the bracket to any convenient vertical surface. Between the vertical part of the bracket 37 and its lower cross arm is 75 a section with a vertical cylindrical opening whereby the bracket fits snugly over the top of the casing 28 and firmly rests on its shoulder. A nut 38 screws over the top of the casing 28 and down upon the bracket 37 so as to hold them tightly together. By attaching the bracket 37, through its cross arms, to any convenient vertical surface, all the fixed parts below and above the casing 28 are held rigid. In the vertical part 85 of the bracket 37 is a longitudinal slot 39, extending from left to right. In the top of the bracket 37 is a longitudinal slot 40, extending into the slot 39, of a width, from back to front, a trifle over the diameter of 90 a bolt 41, and of a width, from left to right, nearly as much again as that diameter.

At the top of the slot 39, and extending across the lower end of the slot 40, is the upper flat side of a knife edge pivot 42, 95 having in its upper part a threaded vertical cavity and having a knife edge at its lower end. A washer 43 rests on top of the bracket 37 around the slot 40. On passing the bolt 41 through the washer 43 and the slot 40, and screwing it into the cavity of the pivot 42, the pivot is firmly secured to the bracket 37. It is furthermore evident that, on slightly unscrewing the bolt 41, the position of the bolt, the washer 43 and the pivot 42 may be shifted back and forth, as desired, as far as the left to right width of the slot 40 permits.

A lever 44, shown in broken front elevation, has on top, at its extreme left or inner end, a transverse angular groove adapted to hold the knife edge of the pivot 42; it has, a short distance from its inner end, on its under side a transverse rectangular groove; and it has, above this latter groove, 110 a circular opening extending from back to front. A yoke 45 rests against the under side of the lever 44 in its rectangular groove; it has arms extending up against the lever in back and in front; it has, on its 115 under side, a transverse angular groove adapted to seat over the knife edge of the bearing 36; and it has, in its arms, slots registering with the circular opening through the lever 44, but of greater dimensions from left to right than is the diameter of the opening. A small bolt 46 passes through the slots of the yoke 45 and the opening of the lever 44. The lever 44, with the parts 45 and 46 in position upon it, is 120 125 130

inserted, at its inner end, into the slot 40 so that its upper groove bears against the knife edge of the pivot 42 and so that the groove of the yoke 45 bears upon the knife edge of the bearing 36.

5 The distance between the knife edges of the pivot 42 and the bearing 36 determines the distance that the outer end of the lever 44 is moved up or down when the dia-
10 phragm 27 is moved up or down. That is to say, if this former distance is one inch and if the effective length of the lever 44, as measured from its top groove, is eight inches, then, on a movement of the dia-
15 phragm of one thirty-second of an inch, the outer end of the lever will move a quarter of an inch. But, furthermore, the left to right dimensions of the slot in the yoke 45 and of the rectangular groove in the lever 20 44 are made to correspond to the left to right dimensions of the slot 40. Consequently, when the bolt 41, the washer 43 and the pivot 42 are moved as far to the right as the slot 40 permits, the bolt 46 may be
25 moved in the slot of the yoke 45 and the yoke may be moved in the rectangular groove of the lever 44 an equal distance to the left; and, upon a tightening up of the parts after such movements, a new adjustment
30 of the lever is accomplished, for it is evident that, upon such adjustment, the distance between the knife edges of the pivot 42 and the bearing 36 is correspondingly de-
35 creased and the range of movement of the outer end of the lever 44 is correspondingly increased. It is also evident that, between the extreme distance apart between the knife edges of the pivot 42 and the bearing 36, there are intermediate distances that can
40 be established. Consequently, if, on movements of the diaphragm 27, the outer end of the lever 44 has too great or too little movement, the proper decrease or increase of the lever movements can be had by a re-
45 adjustment of the parts specified.

A bracket 47, attachable to some convenient surface in a manner not shown, has in its upper arm a vertical cylindrical opening, through which reciprocates the upper 50 end of a rod forming part of a link member 48. The member 48 has a disk at the lower end of its rod; it is pivoted, below its disk, by a pin 49, to the outer end of the lever 44; and its lower end consists of a link, which is attachable to whatever mechanism it is desired that the thermostat shall operate. A helical compression spring 50 surrounds the rod of the member 48, and bears against the upper side of its disk and the under side of the upper arm of the bracket 47, so as to constantly tend both to force downward the lever 44 and the intermediate parts above the diaphragm 27 and also the member 48 and any mechanism connected therewith. The spring 50 is much

weaker than the spring 11 and must never be so strong as to become a factor in compressing the latter spring.

As a motor liquid, to be filled into the chamber contained within the incasing parts 28, 27, 15, 18, 13, 7 and 9, any liquid is suitable that has a high coefficient of expansion and that is serviceable in other particulars. For use in a refrigerator thermostat, I prefer alcohol, on account of its very considerable expansiveness, its cheapness, its safety in handling and its non-action on all metals that may be used to form the containing chamber. Benzene has many of the advantages of alcohol; but it is not so safe in handling. For temperatures below 54 degrees, ethyl chlorid is very desirable on account of its high expansiveness; but it is also somewhat expensive; and, just above that temperature, it vaporizes and in a vaporous condition, as would any gas or vapor, it would nullify some important advantages of my construction. With all three liquids, the diaphragms 7 and 27 may be of vanadium steel or of phosphor bronze; the gaskets 6 and 26 may be of lead; and the other containing parts may be of brass or iron or steel. Mercury, in so far as its expansiveness is concerned, is the ideal motor fluid; but it is expensive; and, when used, its containing parts should be of iron or steel. These observations, as to liquids, also apply if the thermostat is to be used to control a heating system for the maintenance of room temperatures. But for a thermostat to limit the heating of an ammonia still, in an automatic absorption refrigerating machine, where the temperature limit is say 300 degrees, I prefer mercury to the exclusion of all other liquids, the containing chamber, in such case, being quite small. With any liquid, the hub 17 is turned uppermost, the motor liquid is poured in to fill the entire chamber, the regulator 18 is screwed in and the adjacent parts are secured in place as has been described.

Assuming that the thermostat is to be used in connection with a refrigerator, and for the maintenance of a temperature range say of four degrees, the parts of the containing chamber, especially including the parts 1, 2, 3, 8 and 9 and also 15 apart from the hub 16, but excluding the parts 16, 27 and 28, which should remain constant, are so proportioned that, with the particular motor liquid to be used, preferably alcohol, on a four point rise of temperature, the increase in volume of the motor liquid will distend upward the diaphragm 27 one thirty-second of an inch at the center, and, on a subsequent four point back drop of temperature, the decrease in volume of the liquid will permit the spring 50, and the intermediate parts, to move the diaphragm through the same distance back to its original position. The

thermostat, having been filled so nearly full that the regulator 18 is substantially in its extreme outer position, is mounted and suitably connected in the refrigerator; and, by 5 apparatus assumed to be in operation, the refrigerator is cooled down say to 37 degrees. Then, or previously, the regulator 18 is gradually screwed in until, at that temperature, the diaphragm 27 is in its highest position, as evidenced by the extreme elevated 10 position of the outer end of the lever 44. The nuts 23 and 22 are adjusted into securing positions. Then, as the refrigeration progresses and the temperature in the refrigerator gradually drops to 33 degrees, with a decrease in volume of the liquid, the spring 50 presses on the member 48 so as to depress the parts 44, 46, 45, 36, 33, 32, 31 and 15 30 until the diaphragm 27 is forced into its lowest position, but no farther, owing to the ring 30 coming into contact with the partition 29. It is assumed that, in consequence 20 of this depression of the member 48, unshown connected mechanism now temporarily terminates the refrigeration. Consequently, as the temperature in the refrigerator begins to rise, the volume of the motor liquid begins to increase and its pressure 25 forces upward the diaphragm 27 and the intermediate parts so as to compress the spring 50 until the ring 32 comes into contact with the sleeve 34 and the diaphragm lies dead against the foot 30 and the casing 28. The member 48 now operates to again start the 30 process of refrigeration and the ordinary cycle of operation is complete. As before explained, the range of movement of the outer end of the lever 44, and hence of the member 48, may be altered by adjustments 35 of the pivot 42 and the yoke 45 and pin 46. Now suppose, however, that the apparatus operating to cool the refrigerator is shut down, so that the temperature around the thermostat rises above 37 degrees and becomes that of the atmosphere. In consequence 40 of the regulator 18 having been screwed inward from its initial position, it happens that the motor liquid expands with such tremendous force that it would burst its 45 containing casing, were it not for the relief diaphragm 7 and the other parts operative in connection therewith, which other parts constitute a relief mechanism. As it is, this super-increase in volume simply acts through 50 the diaphragm 7 on the member 8 so as to compress the spring 11. On a resumption of refrigeration, and a cooling down of the temperature to 37 degrees, the spring 11 55 forces the member 8 and the diaphragm 7 back into place, where they remain inactive so long as the process of refrigeration continues.

In case, owing to the proportions of the parts, the regulator 18 cannot be screwed 5 in far enough from its initial position to

force the diaphragm 27 into its highest position at 37 degrees, the desired result can be attained by screwing the regulator back to its initial position, by loosening the nut 2, by screwing the casing 3 farther up 70 on the pipe 1, by again tightening the nut, so as to produce a rough adjustment, and then by screwing in the regulator far enough to get a fine adjustment.

Where some refrigerator temperature 75 range, other than for four degrees, is to be maintained, the manner of proportioning the parts, and the method of adjustment, are deemed to be apparent from the foregoing explanation.

Where the thermostat is intended to operate at temperatures higher than that at which the motor liquid is poured in, there must be a reversal of the method of adjusting the volume of the liquid. That is 80 to say, if the regulator 18 alone is to be used for adjusting the volume of the liquid at the operating temperature of the thermostat, the initial position of the regulator, after pouring in the liquid, should 85 be as far inward as possible; then, as the volume of the liquid increases, the regulator should be screwed outward until it is in its proper outward position, with the diaphragm 27 in its extreme high position, 90 at the desired maximum temperature limit. But if the regulator 18 is to be supplemented as above indicated, for a preliminary rough adjustment of the volume of the liquid, the initial position of the casing 95 3 should be high up on the pipe 1; then, as the volume of the liquid increases, loosen the nut 2, screw the casing farther down on the pipe and again tighten the nut. Finally make the fine adjustment with the 100 regulator 18.

The parts 28, 26, 27, 16, 15, 17, 18, 21, 22, 23, 1, 2, 5, 4, 3, 6, 9 and 7, when the latter is maintained in its upper position by its adjacent relief mechanism, constitute 110 a motor member that is similar in operation to a copper or hard rubber rod or tube forming the motor member of many types of thermostats, as illustrated in the patents to Ruud, 443,797, Dec. 30, 1890, and 460,513, 115 Sept. 29, 1891. But in my construction, to obtain a given longitudinal movement at the end of the motor member, I am not obliged to make it of any particular length, which for my purposes would have to be 120 very considerable, but can rely on a sufficiently great diameter of the pipe 1 and other adjacent parts. My relief mechanism, moreover, is of value in connection with a thermostat using any solid substance 125 as a motor member, it being apparent, assuming that the movement of the head of the motor member is limited, that, instead of an initial adjustment of the spring 11 130 as I have described, the spring might be

gradually adjusted after refrigeration had begun in much the same manner as the regulator 18 is adjusted. Furthermore, with a motor member consisting entirely of a rod or tube, expanding longitudinally, such a rod or tube is liable to bend under pressure and thus to render the thermostat, in part or in whole, inactive and ineffectual. Such a difficulty is quite avoided in my construction. On the other hand, if my thermostat is operated at temperatures above that of the atmosphere, as in terminating the heating of an ammonia still in an automatic absorption refrigerating system, the diaphragm 27 and the parts below it have no greater function than other immovable parts of the chamber wall and can well be replaced by a mere wall. Curiously enough, however, if my thermostat is used to control room temperatures, the relief mechanism is of prime importance. For suppose the parts are so constructed and adjusted as to maintain in a room, through proper heating apparatus, a temperature range say of 70 to 72 degrees. Then, in summer time, as the atmospheric temperature rises above 72 degrees, there is precisely the same excess volume and pressure on the walls of the chamber casing as with the refrigerator.

The ordinary means for connecting a diaphragm with a casing wall are illustrated in the case of the diaphragm 7 and the diaphragm 7^a, to be described. Such means are sufficient where the diaphragm is not required to be sensitive to slight changes of fluid pressure and where, consequently, it may be relatively thick. But with a very thin diaphragm, it is apparent that the shearing strain upon the diaphragm, as it is moved both inward and outward, along the same circular line, is certain eventually to cause a breakage that is impossible in case of the diaphragm 27. And by the formation of the casing 28 and the foot 30, and by limiting the movements of the latter, I dispense with the need of any diaphragm reinforcement, such as is illustrated in the patents to Knowles, 18,048, Aug. 25, 1857, and to Thomson, 832,708, Oct. 9, 1906. It further is to be noted, in the construction of the diaphragm 27 and its adjacent parts, that while the foot 30 is on the outside of the diaphragm, my means for connecting a diaphragm with a casing wall are equally available in those valve constructions where a member, corresponding to the foot 30, is adjacent to the inside of a diaphragm and operates, as the diaphragm tends to move outward, to tend to close a valve seat. Such a valve construction is illustrated in the patent to Gold, 508,133, Nov. 7, 1893.

In the case of the means for pivoting and actuating the lever 44, it will be noted that the means for adjusting the distance apart

of the pivot 42 and the bearing 36, do not depend upon the knife edge and groove construction shown and described; nor do said means depend on the peculiar construction of my motor member. For these same means are available with the ordinary pin pivots and bearings and with a motor member wholly of solid material, as illustrated in the patents to Ruud, above referred to.

Finally considering Figs. 7 to 9 inclusive: Here the parts that are so similar to parts already described, as to need no further description, are indicated by the numerals 2^a, 3^a, 4^a, 5^a, 6^a, 7^a, 8^a, 9^a, 10^a, 11^a, 12^a, 13^a, 14^a, 16^a, 17^a, 18^a, 22^a, 23^a, 24^a, 25^a, 26^a, 80 27^a, 28^a, 29^a, 30^a, 31^a, 32^a, 33^a, 34^a, 35^a, 36^a, 38^a, 39^a, 40^a, 41^a, 42^a, 43^a, 44^a, 45^a, 46^a, 47^a, 48^a, 49^a and 50^a, the latter parts severally corresponding to the like numbered former parts without an "a".

A refrigerator right side wall 51 has a long and narrow vertical opening that is adapted to be occupied and sealed by a section 52, having around its external edges a hollow rectangular plate 53. Through holes in the edges of the plate 53, screws 54 secure the plate to the wall 51. A high, narrow tank 55 is inclosed on all sides, except that on top it has a threaded opening, enlarging into a stuffing box recess. A pipe 56, having a descending elbow at its inner end, has the threaded lower end of this elbow screwed into the opening of the tank 55 and is threaded for most of its horizontal length. A packing ring 57, around the pipe 56 in the recess of the tank 55, is pressed down by a gland nut 58 so as to make a tight joint between the pipe and the tank. A large ring 59 clamps around the tank 55 near its lower end and has integral 100 with itself a rod 60, extending horizontally, parallel with the horizontal part of the pipe 56 and threaded at its end. A flanged inner upper ring 61 screws on to the horizontal part of the pipe 56 and a flanged inner lower ring 62 screws on to the rod 60. The pipe 56 and the rod 60 are so spaced apart that, carrying the rings 61 and 62, they pass through openings in the section 52 and are clamped in place by a flanged outer upper 110 ring 63, screwing around the pipe, and by a flanged outer lower ring 64, screwing around the rod. The parts are so proportioned that the section 52, carrying the parts 53, 55, 56, 57, 58, 59, 60, 61, 62, 63 and 64, 120 can be inserted into the opening in the wall 51, so as to maintain the parts in the position shown in Fig. 7 and also to occupy and seal the opening.

An intermediate casing 65 has its parts at 125 the top and right like those of the casing 15 and it has a chamber extending from top to bottom; but, at its lower end, it is externally threaded and has connections like the pipe 1. Here, however, there is not merely a gasket 130

6^a above the diaphragm 7^a, but there is also a gasket 66 below the diaphragm against which the member 9^a is screwed. Here, also, the outside diameter of the casing 65 is 5 sufficiently great to render unnecessary a flange on the casing 3^a. Furthermore, at the right of the casing 15, in axial alinement with the opening containing the regulator 18, is another opening 67, threaded near its outer 10 end and enlarging into a gasket recess 68.

After the pipe 56 has been passed through the section 52 and has been clamped in place, a counter bored nut 69 is screwed over the pipe, with its recess outward. The pipe 56 15 has also near its extreme end a plain section of reduced diameter. A gasket 70 occupies the recess 68 and a ring 71 just enters the recess so as to cover the gasket. The casing 65 and the pipe 56 are then 20 screwed together so that the gasket 70 and the ring 71 surround the plain section of the pipe. And the nut 69 is screwed down over the ring 71, with its recess over the ring, until the gasket 70 is so compressed as 25 to make a tight joint. These means for connecting the casing 65 and the pipe 56 are set forth and claimed in my application Ser. No. 717,142, filed Aug. 26, 1912, entitled Ammonia pipe union.

30 A bracket 72, similar to the bracket 37, but having its cross arms to the left of its vertical part, is secured by screws 73 to the outside of the wall 51. A half collar 74 is secured by bolts 75 to the bracket 72, so 35 as to firmly hold the upper casing 28^a just above its shoulder, and is pressed upon by the nut 38^a.

As compared with the former construction, especially in connection with refrigerators, the modified construction has certain 40 important advantages. By placing scarcely anything more than the tank 55 within the refrigerator, the inside space is economized, all adjustable parts are more easily accessible, and, if the mechanism to be connected 45 with the member 48^a is outside, provision does not have to be made for the passage of the operating lever through the wall of the refrigerator. The parts containing the 50 motor liquid are so proportioned that the liquid in the casing 65 does not affect the action of the liquid in the tank 51. And in other respects the modified thermostat operates as does the former construction.

55 What I have invented and what I desire to have protected by Letters Patent is expressed in claims as follows:

I claim:

1. In combination a temperature controlled motor member, movement multiplying mechanism in operative relation with said member, means operating on a predetermined rise of temperature about said member to permit it to move said mechanism a predetermined distance and on a sub-

sequent fall of such temperature to cause said mechanism to follow said member back to its initial position, means operating in case of an excess of temperature about said member above such predetermined rise to 70 permit of a temporary expansion of said member in a part thereof other than in the part operative upon said mechanism, and means for increasing or decreasing the range of maximum movement of said mechanism. 75

2. In combination a chamber casing, a diaphragm inclosing said casing, a liquid occupying the space within said casing and diaphragm, movement multiplying mechanism in operative relation with said diaphragm, means operating on a predetermined rise of temperature about said liquid to permit said diaphragm to move said mechanism a predetermined distance and on a subsequent fall of such temperature to 80 cause said mechanism to follow said diaphragm back to its initial position, means operating in case of an excess of temperature about said liquid above such predetermined rise to permit of a temporary expansion of a part of said casing, and means for increasing or decreasing the range of maximum movement of said mechanism. 85

3. In combination a chamber casing having two diaphragm openings, a motor diaphragm closing one of said openings, a relief diaphragm closing the other of said openings, a liquid occupying the space within said casing and diaphragms, movement multiplying mechanism in operative relation with 90 said motor diaphragm, means operating on a predetermined rise of temperature about said liquid to permit said motor diaphragm to move said mechanism a predetermined 100 distance and on a subsequent fall of such temperature to cause said mechanism to follow said diaphragm back to its initial position, relief mechanism preventing an outward movement of said relief diaphragm during such temperature changes but temporarily permitting such a movement in 105 case of an excess of temperature about said liquid above such predetermined rise, and means for increasing or decreasing the range 110 of maximum movement of said multiplying 115 mechanism.

4. In combination a chamber casing, a diaphragm inclosing said casing, a liquid occupying the space within said casing and diaphragm, means for adjusting a part of the casing wall containing said liquid so as to be farther in or farther out, movement multiplying mechanism in operative relation with said diaphragm, means operating on a predetermined rise of temperature about said 120 liquid to permit said diaphragm to move said mechanism a predetermined distance and on a subsequent fall of such temperature to cause said mechanism to follow said diaphragm back to its initial position, and 125

means for increasing or decreasing the range of maximum movement of said mechanism.

5. In combination a chamber casing, a diaphragm inclosing said casing, a liquid occupying the space within said casing and diaphragm, means for adjusting a part of the casing wall containing said liquid so as to be farther in or farther out, movement multiplying mechanism in operative relation 10 with said diaphragm, means operating on a predetermined rise of temperature about said liquid to permit said diaphragm to move said mechanism a predetermined distance and on a subsequent fall of such temperature to cause said mechanism to follow said diaphragm back to its initial position, means operating in case of an excess of temperature about said liquid above such predetermined rise to permit of a temporary expansion of a 15 part of said casing, and means for increasing or decreasing the range of maximum movement of said mechanism.

6. In combination a chamber casing having two diaphragm openings, a motor diaphragm closing one of said openings, a relief diaphragm closing the other of said openings, a liquid occupying the space within said casing and diaphragms, means for adjusting a part of the casing wall containing said liquid so as to be farther in or farther out, movement multiplying mechanism in operative relation with said motor diaphragm, means operating on a predetermined rise of temperature about said liquid 25 to permit said motor diaphragm to move said mechanism a predetermined distance and on a subsequent fall of such temperature to cause said mechanism to follow said diaphragm back to its initial position, relief mechanism preventing an outward movement of said relief diaphragm during such temperature changes but temporarily permitting such a movement in case of an excess of temperature about said liquid above such predetermined rise, and means for increasing or decreasing the range of maximum movement of said multiplying mechanism.

7. In combination a chamber casing having a diaphragm opening and a threaded regulator opening, a diaphragm closing said diaphragm opening, a liquid occupying the space within said casing and diaphragm, a regulator screwed into said regulator opening into contact with said liquid and adapted 55 to be screwed farther in or farther out, means for making a tight joint between said regulator and said casing, movement multiplying mechanism in operative relation with said diaphragm, means operating on a predetermined rise of temperature about said liquid to permit said diaphragm to move said mechanism a predetermined distance and on a subsequent fall of such temperature to cause said mechanism to follow said diaphragm back to its initial position, and

means for increasing or decreasing the range of maximum movement of said mechanism.

8. In combination a chamber casing having a diaphragm opening and a threaded regulator opening, a diaphragm closing said diaphragm opening, a liquid occupying the space within said casing and diaphragm, a regulator screwed into said regulator opening into contact with said liquid and adapted to be screwed farther in or farther out, means 70 for making a tight joint between said regulator and said casing, movement multiplying mechanism in operative relation with said diaphragm, means operating on a predetermined rise of temperature about said liquid to permit said diaphragm to move said mechanism a predetermined distance and on a subsequent fall of such temperature to cause said mechanism to follow said diaphragm back to its initial position, means 75 operating in case of an excess of temperature about said liquid above such predetermined rise to permit of a temporary expansion of a part of said casing, and means for increasing or decreasing the range of maximum movement of said mechanism.

9. In combination a main chamber casing having a motor diaphragm opening, a threaded regulator opening and a threaded section with an opening through it, a motor diaphragm closing said motor diaphragm opening, a threaded casing screwed on to said threaded section, having through it a relief diaphragm opening and adapted to be screwed farther in or farther out, means 90 for making a tight joint between said threaded casing and said main casing, a liquid occupying the space within said casings and diaphragms, a regulator screwed into said regulator opening into contact with 95 said liquid and adapted to be screwed farther in or farther out, means for making a tight joint between said regulator and said main casing, movement multiplying mechanism in operative relation with said motor diaphragm, means operating on a predetermined rise of temperature about said liquid 100 to permit said motor diaphragm to move said mechanism a predetermined distance and on a subsequent fall of such temperature to cause said mechanism to follow said diaphragm back to its initial position, relief mechanism preventing an outward movement of said relief diaphragm during such temperature changes but temporarily permitting such a movement in case of an excess of temperature about said liquid above such predetermined rise, and means for increasing or decreasing the range of maximum movement of said multiplying mechanism.

10. In combination a bracket, a pivot attachable to said bracket and adapted to be shifted into various forward and back positions in relation thereto, means for detachably clamping said pivot to said bracket 115 120 125 130

- in any such position, a lever pivoted on said pivot, a motor having a bearing, a yoke bearing on said bearing, attachable to said lever and adapted to be shifted as far back on the lever as said pivot is shifted forward on said bracket and as far forward on the lever as the pivot is shifted back on the bracket, and means for detachably securing said yoke to said lever in any such position.
11. In combination a bracket, a pivot attachable to said bracket, terminating in a knife edge and adapted to be shifted into various forward and back positions in relation thereto, means for detachably clamping said pivot to said bracket in any such position, a lever having a groove registering with said edge, a motor having a knife edge bearing, a yoke having a groove registering with the edge of said bearing, attachable to said lever and adapted to be shifted as far back on the lever as said pivot is shifted forward on said bracket and as far forward on the lever as the pivot is shifted back on the bracket, and means for detachably securing said yoke to said lever in any such position.
12. In combination a bracket with a vertical slot extending from an upper to an under surface thereof, a pivot adapted to be slid forward and back along said under surface, clamping means passing through said slot but occupying only a part of the space therein as measured forward and back and detachably clamping said pivot to said under surface in any such forward or back position, a lever pivoted on said pivot, a motor having a bearing, a yoke bearing on said bearing, attachable to said lever and adapted to be shifted as far back on the lever as said pivot is shifted forward on said under surface and as far forward on the lever as the pivot is shifted back on said under surface, and means for detachably securing said yoke to said lever in any such position.
13. In combination a bracket with a vertical slot extending from an upper to an under surface thereof, a pivot adapted to be slid forward and back along said under surface and terminating in a knife edge at its lower end, clamping means passing through said slot but occupying only a part of the space therein as measured forward and back and detachably clamping said pivot to said undersurface in any such forward or back position, a lever having a groove registering with said edge, a motor having a knife edge bearing with its edge uppermost, a yoke having a groove on its under side registering with the edge of said bearing, attachable to said lever and adapted to be shifted as far back on the lever as said pivot is shifted forward on said under surface and as far forward on the lever as the pivot is shifted back on said under surface, and means for de-
- tachably securing said yoke to said lever in any such position.
14. In combination a bracket, a pivot attachable to said bracket and adapted to be shifted into various forward and back positions in relation thereto, means for detachably clamping said pivot to said bracket in any such position, a lever having through it a transverse opening and pivoted on said pivot, a motor having a bearing, a yoke bearing on said bearing and having arms inclosing said lever and with slots in the arms registering with said opening, and clamping means passing through said slots and opening but occupying only a part of the space therein as measured forward and back and detachably clamping said arms and lever, the forward and back dimensions of said slots and opening being such that said yoke may be shifted as far back on said lever as said pivot is shifted forward on said bracket and as far forward on the lever as the pivot is shifted back on the bracket.
15. In combination a bracket, a pivot attachable to said bracket and adapted to be shifted into various forward and back positions in relation thereto, means for detachably clamping said pivot to said bracket in any such position, a lever having through it a transverse opening, having a transverse slot on its under side and pivoted on its pivot, a motor having a knife edge bearing with its edge uppermost, a yoke positioned in said slot, having a groove on its under side registering with said edge and having arms inclosing said lever and with slots in the arms registering with said opening, and clamping means passing through said arm slots and opening but occupying only a part of the space therein as measured forward and back and detachably clamping said arms and lever, the forward and back dimensions of all said slots and of said opening being such that said yoke may be shifted as far back on said lever as said pivot is shifted forward on said bracket and as far forward on the lever as the pivot is shifted back on the bracket.
16. In combination a bracket with a vertical slot extending from an upper to an under surface thereof, a pivot adapted to be slid forward and back along said under surface and terminating in a knife edge at its lower end, clamping means passing through said slot but occupying only a part of the space therein as measured forward and back and detachably clamping said pivot to said under surface in any such forward or back position, a lever having through it a transverse opening, having a transverse slot on its under side and having a groove registering with said edge, a motor having a knife edge bearing with its edge uppermost, a yoke positioned in said slot, having a groove on its under side registering with the edge of

5 said bearing and having arms inclosing said lever and with slots in the arms registering with said opening, and clamping means passing through said arm slots and opening but occupying only a part of the space therein and detachably clamping said arms and lever, the forward and back dimensions of said lever and arm slots and of said opening being such that said yoke may be shifted 10 as far back on the lever as said pivot is shifted forward on said bracket and as far forward on the lever as the pivot is shifted back on the bracket.

17. In combination a pivoted lever member adapted to be turned inward and outward, an intermediate member bearing on said member near its pivot and on being moved outward turning said member outward, limiting means limiting the inward 15 and outward movements of said intermediate member, a motor member expanding and contracting with increases and decreases of temperature and upon a predetermined expansion moving said intermediate member 20 to its outward limit, and means upon a subsequent contraction of said motor member moving said lever member and intermediate member to the inward limit permitted by said limiting means.

30 18. In combination a pivoted lever member adapted to be turned inward and outward, an intermediate member bearing on said member near its pivot and on being moved outward turning said member outward, limiting means limiting the inward and outward movements of said intermediate member, a motor member expanding and contracting with increases and decreases of temperature and upon a predetermined expansion moving said intermediate member 35 to its outward limit, means upon a subsequent contraction of said motor member moving said lever member and intermediate member to the inward limit permitted by said limiting means, and means for increasing or decreasing the range of maximum movement of said lever member.

19. In combination a pivoted lever member adapted to be turned inward and outward, an intermediate member bearing on said member near its pivot and on being moved outward turning said member outward, limiting means limiting the inward and outward movements of said intermediate member, a motor member expanding and contracting with increases and decreases of temperature and upon a predetermined expansion moving said intermediate member 40 to its outward limit, and means upon a subsequent contraction of said motor member moving said lever member and intermediate member to the inward limit permitted by said limiting means, said elements being so operative at sub-atmospheric temperatures.

65 20. In combination a pivoted lever mem-

ber adapted to be turned inward and outward, an intermediate member bearing on said member near its pivot and on being moved outward turning said member outward, limiting means limiting the inward and outward movements of said intermediate member, a motor member expanding and contracting with increases and decreases of temperature and upon a predetermined expansion moving said intermediate member 70 to its outward limit, means upon a subsequent contraction of said motor member moving said lever member and intermediate member to the inward limit permitted by said limiting means, said elements being so operative at sub-atmospheric temperatures, and means for increasing or decreasing the range of maximum movement of said lever member.

21. In combination a pivoted lever member adapted to be turned inward and outward, an intermediate member bearing on said member near its pivot and on being moved outward turning said member outward, limiting means limiting the inward 85 and outward movements of said intermediate member, a motor member expanding and contracting with increases and decreases of temperature and upon a predetermined expansion moving said intermediate member to 90 its outward limit, means upon a subsequent contraction of said motor member moving said lever member and intermediate member to the inward limit permitted by said limiting means, and relief mechanism permitting 95 an expansion of said motor member in a direction other than toward said intermediate member upon the limiting by said limiting means of an outward movement of the intermediate member.

22. In combination a pivoted lever member adapted to be turned inward and outward, an intermediate member bearing on said member near its pivot and on being moved outward turning said member outward, limiting means limiting the inward and outward movements of said intermediate member, a motor member expanding and contracting with increases and decreases of temperature and upon a predetermined expansion moving said intermediate member 110 to its outward limit, means upon a subsequent contraction of said motor member moving said lever member and intermediate member to the inward limit permitted by 115 said limiting means, relief mechanism permitting an expansion of said motor member in a direction other than toward said intermediate member upon the limiting by said limiting means of an outward movement of the intermediate member, and means for increasing or decreasing the range of maximum movement of said lever member.

23. In combination a pivoted lever member adapted to be turned inward and out-

ward, an intermediate member bearing on said member near its pivot and on being moved outward turning said member outward, limiting means limiting the inward and outward movements of said intermediate member, a motor member expanding and contracting with increases and decreases of temperature and upon a predetermined expansion moving said intermediate member to its outward limit, means upon a subsequent contraction of said motor member moving said lever member and intermediate member to the inward limit permitted by said limiting means, and means for adjusting the expansion and contraction of said motor member so as to correspond with predetermined temperature changes.

24. In combination a pivoted lever member adapted to be turned inward and outward, an intermediate member bearing on said member near its pivot and on being moved outward turning said member outward, limiting means limiting the inward and outward movements of said intermediate member, a motor member expanding and contracting with increases and decreases of temperature and upon a predetermined expansion moving said intermediate member to its outward limit, means upon a subsequent contraction of said motor member moving said lever member and intermediate member to the inward limit permitted by said limiting means, means for adjusting the expansion and contraction of said motor member so as to correspond with predetermined temperature changes, and means for increasing or decreasing the range of maximum movement of said lever member.

25. In combination a pivoted lever member adapted to be turned inward and outward, an intermediate member bearing on said member near its pivot and on being moved outward turning said member outward, limiting means limiting the inward and outward movements of said intermediate member, a motor member expanding and contracting with increases and decreases of temperature and upon a predetermined expansion moving said intermediate member to its outward limit, means upon a subsequent contraction of said motor member moving said lever member and intermediate member to the inward limit permitted by said limiting means, relief mechanism permitting an expansion of said motor member in a direction other than toward said intermediate member upon the limiting by said limiting means of an outward movement of the intermediate member, and means for adjusting the expansion and contraction of said motor member so as to correspond with predetermined temperature changes.

26. In combination a pivoted lever member adapted to be turned inward and outward, an intermediate member bearing on

said member near its pivot and on being moved outward turning said member outward, limiting means limiting the inward and outward movements of said intermediate member, a motor member expanding and contracting with increases and decreases of temperature and upon a predetermined expansion moving said intermediate member to its outward limit, means upon a subsequent contraction of said motor member moving said lever member and intermediate member to the inward limit permitted by said limiting means, relief mechanism permitting an expansion of said motor member in a direction other than toward said intermediate member upon the limiting by said limiting means of an outward movement of the intermediate member, means for adjusting the expansion and contraction of said motor member so as to correspond with predetermined temperature changes, and means for increasing or decreasing the range of maximum movement of said lever member.

27. In combination a chamber casing, a diaphragm inclosing said casing, a liquid occupying the space within said casing and diaphragm, a pivoted lever member adapted to be turned inward and outward, an intermediate member bearing on said diaphragm and also on said member near its pivot and on being moved outward by the diaphragm turning the member outward, limiting means limiting the inward and outward movements of said intermediate member, means for so adjusting the volume of said liquid that upon a predetermined rise of temperature said diaphragm moves said intermediate member to the outward limit permitted by said limiting means, and means upon a subsequent fall of temperature moving said lever member and intermediate member to the inward limit permitted by said limiting means.

28. In combination a chamber casing, a diaphragm inclosing said casing, a liquid occupying the space within said casing and diaphragm, a pivoted lever member adapted to be turned inward and outward, an intermediate member bearing on said diaphragm and also on said member near its pivot and on being moved outward by the diaphragm turning the member outward, limiting means limiting the inward and outward movements of said intermediate member, means for so adjusting the volume of said liquid that upon a predetermined rise of temperature said diaphragm moves said intermediate member to the outward limit permitted by said limiting means, means upon a subsequent fall of temperature moving said lever member and intermediate member to the inward limit permitted by said limiting means, and means for increasing or decreasing the range of maximum movement of said lever member.

29. In combination a chamber casing having two diaphragm openings, a motor diaphragm closing one of said openings, a relief diaphragm closing the other of said openings, a liquid occupying the space within said casing and diaphragms, a pivoted lever member adapted to be turned inward and outward, an intermediate member bearing on said motor diaphragm and 5 also on said member near its pivot and on being moved outward by the motor diaphragm turning the member outward, limiting means limiting the inward and outward movements of said intermediate member, 10 means for so adjusting the volume of said liquid that upon a predetermined rise of temperature said motor diaphragm moves said intermediate member to the outward limit permitted by said limiting means, 15 means upon a subsequent fall of temperature moving said lever member and intermediate member to the inward limit permitted by said limiting means, and relief mechanism preventing an outward movement 20 of said relief diaphragm until after a full outward movement of said motor diaphragm and then temporarily permitting such former movement.
30. In combination a chamber casing having two diaphragm openings, a motor diaphragm closing one of said openings, a relief diaphragm closing the other of said openings, a liquid occupying the space within said casing and diaphragms, a 35 pivoted lever member adapted to be turned inward and outward, an intermediate member bearing on said motor diaphragm and also on said member near its pivot and on being moved outward by the motor diaphragm turning the member outward, limiting means limiting the inward and outward movements of said intermediate member, means for so adjusting the volume of said liquid that upon a predetermined rise of 40 temperature said motor diaphragm moves said intermediate member to the outward limit permitted by said limiting means, means upon a subsequent fall of temperature moving said lever member and intermediate 45 member to the inward limit permitted by said limiting means, relief mechanism preventing an outward movement of said relief diaphragm until after a full outward movement of said motor diaphragm and then temporarily permitting such former movement. 50
31. In combination a chamber casing structure having a diaphragm opening and adapted to be filled with a fluid under pres-
- sure, a diaphragm closing said opening with its edges resting upon said structure, a reciprocating member resting on the central part of said diaphragm, means for forcing 65 said member inward, limiting means limiting the inward movements of said member, and an outer casing surrounding the end of said member near said diaphragm and clamping the edges of the diaphragm to said 70 structure, said outer casing having an annular concave formation between its clamping part and said member such that on an outward distending of the diaphragm and on a movement of the member to the outward 75 limit permitted by said limiting means the diaphragm bears evenly on the member and the concave formation.
32. In combination a chamber casing structure having a diaphragm opening and 80 adapted to be filled with a fluid under pressure, a diaphragm closing said opening with its edges resting upon said structure, a reciprocating member resting the central part of said diaphragm, means for forcing said 85 member inward, limiting means limiting the inward and outward movements of said member, and an outer casing surrounding the end of said member near said diaphragm and clamping the edges of the diaphragm 90 to said structure, said outer casing having an annular concave formation between its clamping part and said member such that on an outward distending of the diaphragm and on a movement of the member to the 95 outward limit permitted by said limiting means the diaphragm bears evenly on the member and the adjacent concave formation.
33. In combination a liquid container, a pipe of less diameter than said container and 100 at one end connecting with it, a casing connecting with the other end of said pipe, a diaphragm inclosing said casing, a liquid occupying the space within said container, pipe, casing and diaphragm, movement 105 multiplying mechanism in operative relation with said diaphragm, means operating on a predetermined rise of temperature about said container to permit said diaphragm to move said mechanism a predetermined distance and upon a subsequent fall of such temperature to cause said mechanism to press upon and to follow said diaphragm back to its initial position, and means operating in case of an excess of temperature about said container above such predetermined rise to permit of a temporary expansion of a part of said casing. 110
